CLAIM

I claim the ornamental design for a handheld data reader, as shown and described.

DESCRIPTION

FIG. 1 is a front isometric view of a handheld data reader showing the new design;

FIG. 2 rear isometric view thereof;

FIG. 3 is a front side elevation view thereof;

FIG. 4 is a rear side elevation view thereof;

FIG. 5 is a left side elevation view thereof;

FIG. 6 is a right side elevation view thereof;

FIG. 7 is a top plan view thereof; and,

FIG. 8 is a bottom plan view thereof.

Broken lines and portions contained within broken line are not claimed.
